UNITED STATES PATENT OFFICE.

ARTHUR R. KRAUSE, OF WOODHAVEN, NEW YORK, ASSIGNOR TO MAX SCHAFER CO.,
INC., A CORPORATION OF NEW YORK.

DESIGN FOR A LIGHTING-FIXTURE DOME.

Application filed November 6, 1928. Serial No. 28,772. Term of patent 7 years.

To all whom it may concern:

Be it known that I, ARTHUR R. KRAUSE, a citizen of the United States, and a resident of Woodhaven, county of Queens, and State of New York, have invented a new, original, and ornamental Design for a Lighting-Fixture Dome, of which the following is a specification, reference being had to the accompanying drawing, forming a part thereof.

The single figure of the drawing shows a perspective view of the lighting fixture dome.

I claim:

The ornamental design for a lighting fixture dome substantially as shown.

ARTHUR R. KRAUSE.
